UNITED STATES PATENT OFFICE.

HARRIET MILES, OF NEW YORK, N. Y., ASSIGNOR TO NEALON COMPANY,
A CORPORATION OF NEW YORK.

HOSE-SUPPORTER CLASP.

No. 821,949.

Specification of Letters Patent.

Patented May 29, 1906.

Application filed November 30, 1904. Serial No. 234,909.

To all whom it may concern:

Be it known that I, HARRIET MILES, of the borough of Manhattan, city of New York, State of New York, (whose post-office address is in care of Nealon Company, Safe Deposit Company of New York, 140 Broadway, New York,) have invented certain new and useful Improvements in Hose-Supporter Clasps, of which the following is a specification.

The invention relates primarily to women's and children's garters, though it is not limited to such use.

The object of the invention is to combine cheapness and simplicity of manufacture with increased ease and simplicity of use.

In the accompanying drawings, Figure 1 illustrates one form of clasp embodying the present invention and opened ready to receive the fabric to be clasped. Fig. 2 is a central longitudinal section of the same. Fig. 3 is a rear view showing one of the securing ears or lugs open and the other clamped down in place to hold the back plate, and it also shows the webbing broken away to show the shape of the back plate. Fig. 4 shows the complete metallic blank for the loop portion of the clasp before the back plate is secured.

30 In the drawings, W is the web to which the fastener is secured.

C is the metal loop; G, the back plate; F, the button; H, the slot or hole through which the webbing is passed and then sewed, and C' 35 represents ears or lugs, which are bent over and into recesses G'' in the back plate G to secure it flat against the upper end of the loop C. The back plate G is preferably faced on its rear G' with fabric, as this is more comfortable than the rubber against the flesh. For the same reason it will be seen the clasp embodies virtually no metallic parts that can come in contact with the flesh of the wearer, except as the slight possible contact 45 between the bent-over ears C' and the flesh; but this practically amounts to nothing, as the web W where it is passed through the slot or eye H by reason of its rearward projection prevents nearly or entirely all contact between the ears C' and the flesh. Preferably the back plate G covers the entire rear face of the loop C and is secured directly against it, the webbing passing through holes H in

the back plate as well as in the loop. The ears or lugs C' rigidly secure the back plate 55 to the loop, so that they can be manipulated as one piece, and the flexibility alone of the back plate G permits the opening of the clasp to admit the hose or fabric between the button and the loop and the placing of 60 the button in proper position in the loop. The extreme simplicity of the fastener and the absence of the usual means of securing the back plate to the fabric separately from the loop and the fact that in my improvement the two parts are secured directly together and normally in close parallelism, face to face, will be clearly apparent from the figures without further description.

The details of the rubber button, whether 70 it contains metal reinforcing parts or a rivet or the improved head set forth in my accompanying application of even date herewith, Serial No. 234,908, are not of the essence of this present invention and are not claimed 75 herein, it being sufficient that the button and back plate form one of two single units that compose the complete fastener under the present invention and that such unit is formed of rubber or other flexible material. 80

As shown, the back plate G is transversely corrugated. This forms no part of the present invention and is obviously non-essential to the operation of the device.

What I claim, and desire to secure as my 85 invention, is the following:

1. A garment-supporter clasp comprising a rigid loop, an integral button and flexible back plate, means engaging the upper end of said back plate for securing said back plate 90 rigidly to said loop, said loop and said flexible back plate being each provided with an opening for receiving a supporting-web.

2. A garment-supporter clasp comprising a rigid loop, an integral button and flexible 95 back plate, means integral with said loop engaging the upper end of said back plate for securing said back plate rigidly to said loop, said loop and said flexible back plate being each provided with an opening for receiving 100 a supporting-web.

3. A garment-supporter clasp comprising a rigid loop having a web-engaging slot at its upper end, an integral button and flexible back plate, and means integral with said loop 105 and independent of said slot engaging the up-

- per end of said back plate for securing said back plate rigidly to said loop.
4. A garment-supporter clasp comprising an integral button and flexible back plate, a metal loop formed with lugs at its upper end engaging with the back plate for rigidly retaining the latter in operative position, said loop and said flexible back plate being each provided with an opening for receiving a supporting-web.
5. A garment-supporter clasp comprising an integral button and flexible back plate provided with apertures, a metal loop formed with lugs at its upper end engaging into said apertures in the back plate for retaining it in operative position, said loop and said flexible back plate being each provided with an opening for receiving a supporting-web.
6. A garment-supporter clasp comprising an integral button and flexible back plate, and a metal loop formed with lugs at its upper end engaging with the back plate for retaining the latter in operative position and with a slot for slidably engaging a supporting-web.
- In testimony whereof I have signed this specification in the presence of two subscribing witnesses.
- HARRIET MILES.
